(57) **CLAIM**

The ornamental design for a jobsite table saw, as shown and described.

DESCRIPTION

FIG. 1 is a perspective view of the jobsite table saw, showing our new design;

FIG. 2 is a top view;

FIG. 3 is a bottom view;

FIG. 4 is a right side view;

FIG. 5 is a left side view;

FIG. 6 is a front view; and,

FIG. 7 is a rear view.

The surface shading on the illustrative jobsite table saw is intended only to show the character and contour of the surfaces indicia.
